United States Patent Office.

OLIVER E. PILLARD, OF NEW BRITAIN, CONNECTICUT, ASSIGNOR TO
FREDERIC H. NORTH, OF THE SAME PLACE.

Letters Patent No. 71,639, dated December 3, 1867.

IMPROVEMENT IN ADJUSTABLE TUMBLERS FOR PERMUTATION LOCKS.

The Schedule referred to in these Letters Patent and making part of the same.

TO ALL WHOM IT MAY CONCERN:

Be it known that I, OLIVER E. PILLARD, of New Britain, in the county of Hartford, and State of Connecticut, have invented and made a certain new and useful Improvement in Locks; and I do hereby declare the following to be a full, clear, and exact description of the said invention, reference being had to the annexed drawing, making part of this specification, wherein—

Figure 1 is an elevation of one of the tumblers of a lock, showing my improvement with the cap-plate removed, and

Figure 2 is a transverse section of the same at the line xx .

Similar letters denote the same parts.

My invention relates to the peculiar construction of a circular tumbler, for use in that class of locks in which a series of such circular tumblers is employed upon a spindle that is operated by a handle or knob, and provided with an index, so that the tumblers are successively placed in their proper position by the rotation of said knob and index. This character of lock and its mode of construction being well-known, a further description is rendered unnecessary.

The peculiar feature of my present invention consists in a friction-band, that is introduced within the notched ring forming the exterior portion of the tumbler, and surrounds the disk that is upon the tumbler-axis, and carries the pin by which one tumbler is made to move the next; and with these I combine a cam, that is so located that its rotation shall draw the ends of the friction-band towards each other, and clamp the disk, and thereby firmly connect the two parts by a more extended frictional contact than has heretofore been employed.

By this construction the adjustment of the tumblers is greatly facilitated, and the risk of their becoming misplaced by use is lessened and effectually removed.

In the drawing, a is the tumbler-axis, fitted as usual; b is the disk surrounding the same, and carrying the stud c , by means of which one tumbler communicates motion to the next, as heretofore usual; d is the tumbler-ring, with a notch at e , for the bolt-stud to pass into when the tumblers are turned, so that the notches all stand on a line. The ring d is made hollow, and a friction-band, i , is introduced around the periphery of the disk b , and the ends of this friction-band are turned off radially. One comes against a fixed stud, l , the other is operated upon by an eccentric or cam, h , that is fitted to turn in the space between the two plates forming the hollow tumbler-ring d . A polygonal hole is formed through the hub of the cam h , for receiving a key, by means of which the same may be turned for relieving or tightening the friction-band i .

When the lock is open, and a polygonal key introduced through the cams of all the tumblers, the frictional contact and connection of the various tumblers with their disks will be relieved by turning such key; after which the tumblers can be set in succession to the desired index-points, and then secured by rotating the cams to tighten the friction-straps. The eccentric or cam in most locks will be the most convenient mechanism for tightening the friction-strap; but I do not limit myself to the use of the eccentric as the mechanism for so tightening the strap.

What I claim, and desire to secure by Letters Patent, is—

The friction-strap i , applied around the periphery of the stud-disk b , and within the notched tumbler d , in combination with mechanism for tightening said strap, substantially as and for the purposes set forth.

In witness whereof, I have hereunto set my signature, this eighth day of June, A. D. 1867.

OLIVER E. PILLARD.
